LOOM FOR WEAVING

Albert Moessinger, Winterthur, Switzerland, assignor to Sulzer Frères, Société Anonyme, Winterthur, Switzerland

Application March 14, 1941, Serial No. 383,327
In Switzerland March 21, 1940

4 Claims. (Cl. 139—188)

The present invention relates to looms for weaving and more particularly to a loom employing a nipper device for inserting the weft into the shed and fixed weft bobbins, the said gripper device being guided by means rigidly connected to the slay.

An object of the invention resides in the provision of means which assure that the average direction of the motion of the guide means moving with the slay is set obliquely to the central plane of the shed, in such a way that the whole guide means is swung-in at the same side of the fabric. The average direction of motion of the slay with respect to the central plane of the shed may be chosen so oblique that, when beating up the weft, the shuttle guide can pass along without touching the temples. The weft inserting device may be guided all round by the guide means.

Guidance of the shuttle in the shed by means of a tooth-shaped guide-element fixed on the slay is known per se. All conventional constructions however suffer from the drawback that no guiding is possible along the broad side of the normal roller temple, because the guide means would collide with the roller temple during the beating-up operation.

An interruption of the guide effect for at least 4 inches is of no great consequence in slow-speed machines with large, long shuttles and with rigid weft needles. Thorough tests have shown that such an interruption of the guide effect is absolutely impossible in the case of high-speed machines with very small shuttles or with thin, flexible weft needles.

Guide means have been proposed which carry out an additional movement relatively to the slay so that the shuttle guide is opened during the beat. Such constructions suffer from excessive wear and the guide effect is inaccurate after a short time of use. The present invention provides means for overcoming the shortcomings of the conventional mechanisms. According to the invention the direction of movement of the slay is inclined with respect to the center plane of the shed so that the guide means move outside of the fabric and of the temples.

With an arrangement according to the present invention the weft inserting means are guided all around and in all directions.

Further and other objects of the present invention will be hereinafter set forth in the accompanying specification and claims and shown in the drawing which, by way of illustration, shows what I now consider to be preferred embodiments of my invention.

In the drawing:

Fig. 1 is a diagrammatic part sectional side view of a mechanism according to the invention.

Fig. 2 shows a modified guide-tooth for a weft needle.

Fig. 3 illustrates the shuttle guide seen from the side of the fabric towards line III—III of Fig. 1.

Like parts are designated by like numerals in all figures of the drawing.

Referring more particularly to the drawing, Fig. 1 illustrates the slay mechanism according to the invention, the solid lines showing the mechanism in picking position and the dash and dotted lines showing the mechanism in beating up position. A main shaft 2 which is driven by the loom is rotatably supported on frame member 1. Eccentric 3 is keyed to shaft 2 and transmits by means of a connecting rod 4 and through pivot pin 5 a reciprocating motion to slay lever 7 which swings about pivot pin 6. Lever 7 is shown in solid lines in picking position i. e. in its extreme position; the dot and dash showing 7' of the lever indicates it in its beating up position.

25 Slay 8 is mounted to the slay lever or arm 7. The direction of movement of slay 8 and of arm 7 into position 7' is illustrated by means of the dot line 25. Slay 8 is provided with a groove 9 in which reed 10 is firmly held by means of wedge member 11 and screws 12. A shuttle guide is mounted on the slay 8. This guide is formed by a T bar 13 having slots 23 into which slots the guide plates 14 proper are inserted and soldered to bar 13.

30 35 Fabric 15 is stretched by means of roller temples 16 and their cover 16'. Warp threads 17 form the shed, the center plane of which is indicated by the dash and dot line 18. An eight-sided shuttle 20 moves in or immediately adjacent to the center plane 18. Reed 10 is in inclined position with respect to center plane 16 and is perpendicular or substantially perpendicular thereto, i. e. inclined relatively to the direction of the beat, when in beating up position.

40 45 According to the invention the position of fulcrum 6 is located between an imaginary plane extending through the edge 19 of the fabric and at right angle to the plane 18, and warp beam 30 which is indicated in small scale on Fig. 1. Because of this the slay 8 moves in an inclined direction. The location of fulcrum 6 is so far to the left that the guide teeth 21 of the guide plates 14 pass below the temple roller 16 and the general direction of movement of the slay is inclined 50 55 with respect to the center-plane of the shed.

The projection of the fulcrum 6 in the plane 18 of the fabric lies in the rear-position of the reed or still further to the left in the direction towards the warp beam.

Figure 2 shows a modification of the form of the guide tooth 21' whereby the weft insertion means consists of a flexible strip 22 instead of a shuttle 20 as in Figure 1.

Fig. 3 is a side view of the guide plates 14 seen from the side of fabric 15. The plates 14 are fixed in the slots 23. The T-bar 13 is connected with the slay 8 as shown in Fig. 1.

While I believe the above described embodiments of my invention to be preferred embodiments, I wish it to be understood that I do not desire to be limited to the exact details of design and construction shown and described, for obvious modifications will occur to a person skilled in the art.

I claim:

1. In a loom for weaving, a lay comprising support means disposed underneath the warp threads, reed means connected with and projecting upwardly from said support means, weft insertion means, guide means mounted on said support means forward of said reed with respect to its movement toward the finished fabric and projecting upwardly from said lay and between the lower warp threads, said guide means laterally substantially surrounding said insertion means and having marginal portions adapted to contact said weft insertion means and enclosing the center of gravity thereof, and weft thread passage means provided on the portion of said guide means facing said reed and opening toward said reed.

2. In a loom for weaving, a lay comprising support means disposed underneath the warp threads, reed means connected with and projecting upwardly from said support means, weft insertion means, guide means mounted on said support means forward of said reed with respect to its movement toward the finished fabric and projecting upwardly from said lay and between the lower warp threads, said guide means laterally substantially surrounding said insertion means and having marginal portions adapted to contact said weft insertion means and enclosing the center of gravity thereof, and weft thread passage means provided on the portion of said guide means facing said reed and opening toward

said reed, said guide means being spaced from said reed and mounted to said support means and guiding said weft insertion means completely independently of said reed and having said marginal portions contacting said weft insertion means completely independently from said reed.

3. In a loom for weaving, a lay comprising support means disposed underneath the warp threads, reed means connected with and projecting upwardly from said support means, weft insertion means, guide means mounted on said support means forward of said reed with respect to its movement toward the finished fabric and projecting upwardly from said lay and between the lower warp threads, said guide means laterally substantially surrounding said insertion means and having marginal portions adapted to contact said weft insertion means and enclosing the center of gravity thereof, weft thread passage means provided on the portion of said guide means facing said reed and opening toward said reed, and lay motion control means maintaining the top portion of said guide means below the upper warp threads at all operating positions of said lay.

4. In a loom for weaving, a lay comprising support means disposed underneath the warp threads, reed means connected with and projecting upwardly from said support means, weft insertion means, guide means mounted on said support means forward of said reed with respect to its movement toward the finished fabric and projecting upwardly from said lay and between the lower warp threads, said guide means laterally substantially surrounding said insertion means and having marginal portions adapted to contact said weft insertion means and enclosing the center of gravity thereof, weft thread passage means provided on the portion of said guide means facing said reed and opening toward said reed, and lay motion control means maintaining the top portion of said guide means below the upper warp threads at all operating positions of said lay and moving said top portion tangentially to the upper warp threads, said top portion having a marginal portion disposed parallel to the upper warp threads at the tangential point of movement of said top portion underneath the upper warp threads.
